UNITED STATES PATENT OFFICE.

BERNARD J. GARRIS, OF WILMINGTON, DELAWARE, ASSIGNOR OF ONE-HALF TO LEO SAMEL, OF SOUTH STERLING, NEW JERSEY.

HANDLE FOR FOUNTAIN BRUSHES.

Application filed May 20, 1925. Serial No. 31,629.

This invention relates to fountain brushes, more particularly to shaving brushes of the type in which the brush handle constitutes a receptacle for a shaving soap or paste 5 adapted to be forced into the bristles of the brush head for forming a lather when the brush is used, and the invention has for its object to provide, in a manner as herein- 10 after set forth, a brush of the class de- 15 scribed, including a soap or paste expelling plunger having vacuum spaces on its periphery acting to prevent the revolving of the plunger during its expelling action, and thereby overcoming the necessity of providing 20 the inner face of the handle with a combined guide and retaining rib for the plunger.

Further objects of the invention are to provide, in a manner as hereinafter set 25 forth, a fountain brush, which is simple in its construction and arrangement, strong, durable, compact, sanitary when used, slightly in appearance, thoroughly efficient and convenient in its use, and inexpensive to 30 manufacture.

With the foregoing and other objects in view, the invention consists of the novel construction, combination and arrangement 35 of parts, as hereinafter more specifically de- 40 scribed and illustrated in the accompanying drawings, wherein is shown an embodiment of the invention, but it is to be understood that changes, variations and modifications 45 can be resorted to which come within the 50 scope of the claims hereunto appended.

In the drawings wherein like reference characters denote corresponding parts throughout the several views:—

Figure 1 is an elevation of a fountain 55 brush, of the shaving type, in accordance with this invention.

Figure 2 is a vertical sectional view thereof.

Figure 3 is a section on line 3—3, Figure 1.

Referring to the drawings in detail, 1 denotes a cylindrical hollow handle of suitable length and diameter, open at its inner end and having an integral closure 2 at its outer end. The closure 2 is formed with a centrally disposed opening 3 which registers with a collar 4, provided on the inner face of the closure 2. The periphery of the handle 1, at the inner end portion thereof, is peripherally threaded, as at 5. Con-

nected to the handle 1, as well as projecting from each end thereof, is a threaded plunger feed screw, referred to generally by the reference character 6. The member 6 is positioned at the longitudinal axis of the handle 1 and consists of an intermediate peripherally threaded portion 7, an inner end portion 8 and an outer end portion 9. The portions 8 and 9 are of less diameter than the portion 7, and the portion 8 is of less 65 diameter than the portion 9. The portion 8 is tubular to provide a discharge passage 10, and said portion 8 is of greater length than the portion 9 but of less length than the portion 7. The portion 7, at its inner 70 end, is provided with a short central bore 11, which is closed at one end and its other end registering with the passage 10. The portion 7 is furthermore provided at its inner end with a diametrically disposed port 12 which forms an inlet for the passage 10 and which opens into the bore 11. The portion 9, at its outer end, is peripherally threaded, as at 13, and the periphery of the portion 9, between the threaded portion 13 thereof and the outer end of the portion 7 is smooth 80 throughout. The portion 9 of the member 6 extends through the collar 4 and opening 3 and the threaded part 13 of the portion 9 projects exteriorly from the closure 2. 85

Mounted on the closed outer end of the handle 1, as well as overlapping the same, is a revolvable flanged cap 14, having a central opening 15 formed with a threaded wall for engagement with the threaded part of 90 the portion 9. The cap 14 is fixedly secured to the member 6 by a hold-fast device 16, which is countersunk in the cap 14 and threadedly engages with a threaded socket 17 formed in the outer end portion 9 of the member 6. The periphery of the flange of the cap 14 is knurled, as indicated at 18, to provide a gripping surface therefor.

Threadedly engaging with the threaded inner end of the handle 1, as well as closing the inner end of said handle 1, is a tubular brush element consisting of a hollow sleeve-like head 19, into which the bristles 20 extend and are secured therewith. The bristles 20 project a substantial distance from one end of the head 19. Formed integral with the inner face of the head 19, intermediate the ends thereof, is a partition 21, provided with a central opening 22 and a collar 23 which registers with the opening 110

22 and extends from the upper face of the partition 21. That portion of the head 19 above the partition 21 has the inner diameter thereof greater than that portion below the 5 partition. The inner face of the head 19, above the partition 21, is threaded for engagement with the peripheral threads 5 of the handle 1. When the brush element is secured to the handle 1, the partition 21 abuts 10 against the edge of the handle at the open inner end of the latter and said partition constitutes a closure for the handle.

The hollow handle provides a chamber 24 for the reception of a shaving soap or paste 15 and which is expelled by an inverted cup-shaped plunger 25 mounted on and threadedly engaging with the member 6. The plunger 25 is formed centrally with an opening 26, having the wall thereof threaded for 20 engagement with the intermediate portion 7 of the member 6, and said plunger 25 is furthermore formed with a series of peripheral grooves 27, which act, in connection with the inner face of the handle 1, to set a 25 gripping means to prevent the revolving of the plunger 25 when the member 6 is revolved, but at the same time permitting of the plunger 25 to move towards or away from the partition 21. When the member 30 6 is revolved in a clockwise direction the plunger 25 will move, without revolving, towards the partition 21, thereby expelling the soap or paste through the port 12, into the bore 11 and from there through the passage 35 10 into the bristles 20, as the portion 8 of the member 6 is of such length that it will extend centrally of and into the bristles below the inner end of the head 19. When the member 6 is revolved in an anti-clockwise direction, the plunger 25 will shift, 40 without revolving, towards the closure 2. The portion 8 of the member 6 extends through the collar 23 and opening 22 into the bristles 20, and said collar 23 maintains 45 the portion 8 of the member 6 at the longitudinal axis of the handle, and the collar 4, in connection with the opening 3 maintains the portion 9 of the member 6 at the longitudinal axis of the handle, or in other words 50 the collars 4 and 23 revolvably support, as well as retain the member 6 at the longitudinal axis of the handle 1. The closure 2 and partition 21 provide what may be termed the end walls of the chamber 24.

55 The port 12 is permanently maintained in spaced relation with respect to the collar 23, through the medium of the cap 14 and hold-fast device 16, and the said elements just referred to prevent lengthwise shifting of the 60 member 6 relative to the handle 1.

The plunger 25 has the body thereof relatively thin and the diameter of the plunger 25 with respect to the inner diameter of the handle 1, is such that an extremely close or 65 snug fit will be had, but the fit is such as not

to prevent shifting movement of the plunger when the element 6 is revolved in either direction.

When it is desired to replenish the chamber 24, the brush element is disconnected 70 from the handle 1 and after the desired amount of soap or paste has been positioned in the chamber 21, the brush element is then secured in position and which closes the inner end of the chamber. The element 6, 75 when desired, can be removed from the handle 1 through the open end thereof, and which can be accomplished by removing the hold-fast device 16 and disconnect the cap 80 from the portion 9 of the member 6.

It is thought that the many advantages of a fountain brush, in accordance with this invention, can be readily understood, and although the preferred embodiment of the invention is as illustrated and described, yet 85 it is to be understood that changes in the details of construction can be had which will fall within the scope of the invention as claimed.

What I claim is:—

1. A handle for a fountain brush comprising a hollow handle closed at one end and open at its inner end and having its closed end formed with an aperture and an integral inwardly extending collar having 90 its inner face registering with the wall of the aperture, a removable tubular element threadedly engaging with the handle at the open end of the latter and provided intermediate its ends with an integral partition 95 for closing said open end, said partition and handle providing a receiving chamber, said partition formed with an aperture and an inwardly extending collar projecting towards the first mentioned collar and having its inner face registering with the wall of such aperture, a revoluble element extending through said collars and projecting from said closed end and partition and formed with an inner terminal portion ported 100 lengthwise thereof and communicating with said chamber at a point spaced from the collar on said partition, and means carried by and shifted by said element for expelling the contents of the chamber through said 105 ported terminal.

2. A handle for a fountain brush comprising a hollow handle closed at one end and open at its inner end and having its closed end formed with an aperture and an integral inwardly extending collar having 110 its inner face registering with the wall of the aperture, a removable tubular element threadedly engaging with the handle at the open end of the latter and provided intermediate its ends with an integral partition 115 for closing said open end, said partition and handle providing a receiving chamber, said partition formed with an aperture and an inwardly extending collar projecting to- 120

wards the first mentioned collar and having its inner face registering with the wall of such aperture, a revoluble element extending through said collars and projecting from said closed end and partition and formed with an inner terminal portion ported lengthwise thereof and communicating with said chamber at a point spaced from the collar on said partition, means carried by and shifted by said element for expelling the contents of the chamber through said ported terminal, and means mounted on the closed end of the handle and connected to said element exteriorly of said closed end for manually revolving the element.

3. A handle for a fountain brush comprising a hollow handle closed at one end and open at its inner end and having its closed end formed with an aperture and an integral inwardly extending collar having its inner face registering with the wall of the aperture, a removable tubular element threadedly engaging with the handle at the open end of the latter and provided inter-

mediate its ends with an integral partition for closing said open end, said partition and handle providing a receiving chamber, said partition formed with an aperture and an inwardly extending collar projecting towards the first mentioned collar and having its inner face registering with the wall of such aperture, a revoluble element extending through said collars and projecting from said closed end and partition and formed with an inner terminal portion ported lengthwise thereof and communicating with said chamber at a point spaced from the collar on said partition, and means carried by and shifted by said element for expelling the contents of the chamber through said ported terminal, said means provided with peripheral grooves coaxing with the inner face of said handle to prevent the revolving of such means on said element.

In testimony whereof, I affix my signature hereto.

BERNARD J. GARRIS.
